No. 655,699.

Patented Aug. 14, 1900.

W. W. EDWARDS.

SHIP'S PROPELLER.

(Application filed July 15, 1899.)

(No Model.)

UNITED STATES PATENT OFFICE.

WILEY WAYMAN EDWARDS, OF FUSKY, MISSISSIPPI.

SHIP'S PROPELLER.

SPECIFICATION forming part of Letters Patent No. 655,699, dated August 14, 1900.

Application filed July 16, 1899. Serial No. 723,919. (No model.)

To all whom it may concern.

Be it known that I, WILEY WAYMAN EDWARDS, residing at Fusky, in the county of Neshoba and State of Mississippi, have invented a new and useful Ship's Propeller, of which the following is a specification.

My invention relates to means for the propulsion of vessels, and more particularly to that class of propelling mechanism in which 10 the well-known screw-propeller is the principal feature.

The object of the invention is to provide simple and efficient means for increasing the force of such propelling mechanism, and consequently the speed of the vessel, without any 15 corresponding increase in the power by means of which the mechanism is driven.

With this object in view my invention consists in the improved construction, arrangement, and combination of parts hereinafter 20 fully described and afterward specifically pointed out in the appended claim.

In order to enable others skilled in the art to which my invention most nearly appertains 25 to make and use the same, I will now proceed to describe its construction and operation, reference being had to the accompanying drawings, forming part hereof, in which—

Figure 1 is a longitudinal vertical sectional view 30 through part of a vessel equipped with my invention on the plane indicated by the broken line 1 1 of Fig. 2. Fig. 2 is a transverse vertical sectional view on the plane indicated by the broken line 2 2 of Fig. 1. Fig. 35 3 is a longitudinal horizontal sectional view through part of vessel, showing my invention in a form slightly modified from that illustrated in Figs. 1 and 2. Fig. 4 is a detail sectional view on the plane indicated by the broken line 4 4 of Fig. 3. Fig. 5 is a similar 40 view on the plane indicated by the broken line 5 5 of Fig. 3.

Like numerals of reference mark the same parts wherever they occur in the several figures of the drawings.

Referring to the drawings by numerals, 6 indicates the hull of the vessel, through the stern of which, below the water-line, projects a cylindrical tube 7. In this tube is located 50 a screw-propeller 8 on a shaft 9, which is journaled in a bridge 10, secured in and across the tube, the forward end of the propeller

running in contact with a collar 11 on said bridge. The propeller-shaft extends through the forward end of the tube, which thus 55 forms its forward journal, and a suitable stuffing-box 13 is provided on the shaft where it passes into the hull. The shaft inside the hull is coupled to the engine in any approved manner. The tube is also provided with a 60 stuffing-box 12 where it emerges from the hull, and at its forward end the tube is turned upward, as at 14, and outward through the hull at 15, the upward and horizontal sections 14 and 15 being of greater diameter than the 65 tube proper and the latter opening through the hull above the level of the discharge end of the tube and below the water-level. The upward section 14 forms the penstock of a 70 turbine wheel 16, mounted therein on a vertical shaft 17, which is journaled in suitable bearing 18 in a framework 19 in the vessel and is provided with a stuffing-box 20 where it passes into the hull.

On the turbine-shaft 17 is a bevel gear-wheel 21, which engages a similar bevel gear-wheel 22 on a shaft 23, parallel with the propeller-shaft 9. These shafts 23 and 9 are connected by gear-wheels 24 and 25, (as shown in Fig. 1,) so the propeller and turbine wheel 80 are simultaneously rotated.

In the operation of the invention the propeller, driven by the usual engine, drives the water in tube 7 out at the stern and causes a current to be maintained through the tube 85 and its extensions. At the same time the turbine wheel is turned and assists in forcing this current through tube 7, thus rendering easier the action of the propeller. It will of course be understood that the effect of the 90 turbine may be varied by gearing it to run faster or slower with relation to the speed of the propeller by changing the relative sizes of the engaging gear-wheels or by increasing or diminishing the difference in diameter between the discharge-tube and its extensions. 95

The bridge 10 is shown in this instance as provided with a right-angled flange 10² at each end, riveted or bolted to the inside of the tube, but any other means of securing it may be 100 employed.

In the modified form illustrated in Fig. 3 the discharge-tube 7 is entirely outside of the hull, secured thereto by suitable braces 26

and 27. The tube is also entirely horizontal, and the turbine wheel 16 is mounted on the propeller-shaft 9 in front of propeller 8, the water being taken into the open front end of tube 7 and the shaft 9 passed directly into the hull at 28, where it is provided with a stuffing-box 29.

While I have illustrated and described what I consider to be the best means now known to me for carrying out my invention, I do not wish to be understood as restricting myself to the exact forms and constructions shown, as many slight changes therein or variations therefrom might suggest themselves to the ordinary mechanic, all of which would be clearly included within the limit and scope of my invention.

Having thus fully described my invention, what I claim as new, and desire to secure by Letters Patent of the United States, is—

In a vessel the combination with a tube consisting of a horizontal longitudinal section projecting through the hull at the stern, a

lateral horizontal section opening through the side of the hull and a vertical section connecting the two horizontal sections, the lateral horizontal section and the vertical section being of greater diameter than the longitudinal horizontal section, of a propeller mounted on the rear horizontal section, and a turbine 30 wheel mounted on the vertical section and connected with the propeller for conjoint operation, a horizontal shaft journaled in the longitudinal horizontal section and projected into the hull, a screw-propeller thereon, a vertical shaft journaled in the vertical section and projected into the hull, an intermediate shaft, in the hull parallel with the propeller-shaft, intermeshing bevel-gears on the turbine and intermediate shafts and intermeshing 40 gear-wheels on the intermediate and turbine shafts, substantially as described.

WILEY WAYMAN EDWARDS.
